HOISTING MECHANISM

Filed March 24, 1924

UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

HOISTING MECHANISM

Application filed March 24, 1924. Serial No. 701,361.

This invention relates to a hoisting mechanism.

It has for its object to provide an improved hoisting mechanism. A further object is to provide improved hoisting mechanism having improved driving connections between the driving motor and drum means. Another object is to provide a driving motor whose power generating elements are continuously operable in only a single manner while the supporting elements therefor are rotatable in opposite directions depending upon which one of the plurality of drums is driven. A still further object is to provide an improved hoisting mechanism having a plurality of rotatable drums in combination with a motor of the previously mentioned type and automatic means for forming a positive driving connection between one of the drums and said motor upon one direction of movement of the motor supporting elements or to automatically engage the other drum when opposite direction of movement of the motor supporting element is had. A further object is to provide improved supporting means for said drums, such means including a bearing support upon the periphery of the motor housing. By my improved construction there is practically no relative movement between the drum and the motor housing regardless of which drum might be positively driven and which construction thereby reduces friction losses to a minimum and also excessive wear and tear on the bearings.

In the accompanying drawings I have shown for purposes of illustration two forms which my invention may assume in practice.

In these drawings,—

Fig. 1 is a vertical longitudinal section through the hoist.

Fig. 2 is an enlarged fragmentary horizontal section taken on line 2—2 of Fig. 1.

Fig. 3 is a modified form of clutch mechanism such as illustrated in Fig. 2.

In the illustrative form of my invention I have shown the same as comprising a base 1 having at its opposite ends upwardly extending standards 2 and 3. With the exception that the driving pinions are on the oppo-

site ends of the opposite rotor shafts, the drum mechanism and reduction gearing is substantially the same on each end and the description of one will serve for the other. Rotatably mounted in each of the standards is a hollow stub shaft 4 having a radial flange 5 to which is removably secured an annular flange 7 forming a brake 8 with which a manually operable brake band 9 cooperates, while carried on the inner side of said annular flange is an internal gear 10 with which driving gears cooperate, to be described later. In my improved mechanism the driving motor housing 11 is rotatably mounted within the hollow portion of the shafts 4. More specifically, the motor housing 11 comprises an elongated casing within whose periphery is a central portion 12 having overlapping bores within which are mounted intermeshing rotors 13 rotatably mounted in brackets 14 fixed to the central portion 12 by any suitable screw connections desired. Thus chambers 15 and 16 are formed between the members 14 and the ends of the casing 11, and end closure gear supporting members 17 are secured to these ends as by screws 18. Projecting outwardly from each of the members 17 are stub shafts 19 rotatably mounted within bearings 20 carried in the hollow portion of the stub shafts 4.

The reduction gearing between the rotors 13 and the drum comprises pinions 21 mounted on opposite ends of the opposite rotor shafts. The gearing from now on is identical for each drum and hence only one end needs to be described. The pinion 21 meshes with an internal gear 22 fixed upon a shaft 23 also carrying a pinion 24, said shaft being coaxial with the drum axis and rotatably mounted within a bearing 25 carried by the rotor bracket 14, while the other end of said shaft is rotatably mounted within the member 17. Also carried by the member 17 and adapted to mesh with the pinion 24 is a gear 26 fixed upon a rotatable shaft carrying a pinion 27 meshing with an idler gear 28 rotatably carried by the member 17 and engaging the internal gear 10.

Mounted upon the periphery of the motor casing 11 are right and left hand drums 29

and 30 which have adjacent abutting radial and annular flange members 31 and 32 respectively, while grooves 33 and 34 form braking surfaces for brake bands 35 and 36 to 5 brake rotation of either of the drums. The other ends of said drums are held in their operative position relative to the motor housing, as by the outer radial portions of the members 17 which engage the ends of thrust 10 bearings 37 and 38. The flanges 31 and 32 are so disposed that there is an annular chamber 39 formed therein within which is mounted an automatically shiftable pawl mechanism 40. This pawl mechanism comprises an annular ring 41 disposed upon the periphery of the motor housing and having keys 42 projecting inwardly into keyways 43 formed in the periphery of said casing, which accordingly positively carries the ring 41 therewith. 15 Projecting outwardly from each side of the ring 40 are the pawls proper comprising reversely directed combined cams and pawls 44 and 45 having inclined surfaces 46 and 47 adapted to engage, when in one position or 20 the other, ratchet teeth 48 or 49 formed respectively on the inner side of the radial flanges 31 and 32, it being noted that these ratchet teeth are likewise of an opposite nature so as to cooperate with the reversely 25 directed pawls.

A usual means may be used for supplying live pressure fluid to the motor herein shown as comprising a valve 50 adapted to allow flow of fluid through a passage 51 formed in 30 the shaft 19 and motor housing. A usual feeding cable 57 disposed upon the periphery of the drum 29 is wound thereon, we will say from the upper side, while the cable 58 on the other drum is wound thereon from the under 35 side. Thus with both drums rotating in the same direction one cable will be feeding in while the other is feeding out and vice versa.

In Fig. 3 I have shown a modified form of 40 ratchet and pawl mechanism which comprises individual pawl members 52 slidably mounted in keyways formed in the periphery of the motor housing and having reversely directed pawls 53 and 54 adapted to engage ratchet teeth 55 and 56 formed respectively on the 45 right and left hand drums 29 and 30, these teeth also having cam surfaces for shifting said pawl.

In the operation of my device employing 50 either the preferred form of ratchet mechanism or the modified form, live pressure fluid will be admitted to the motor 1 to continuously operate the same. It will be assumed that the drum 30 is being driven as by holding the left hand internal gear 10 stationary 55 as by the brake means, in which case the ratchet mechanism 40 will be positioned as shown in Fig. 2, thus positively driving the drum 30 as through the key and keyway connection 42 and 43. In this case, the cable 58 will be wound in on the under side while the

cable 57 on drum 29 will be permitted to freely pay out from the upper side thereof to cause rotation of said drum in the same direction as the drum 30 and the motor housing 11. In such a construction it will be noted that there is no relative movement between the driven drum and motor housing and no substantial relative movement between the other drum and the housing. If now it is desired to drive the drum 29 in the reverse direction to wind in the cable 57, the left hand brake 9 will be released while the right hand brake 9 will be operated to prevent rotation of the right hand internal gear 10. Due to the fact that the reduction gearing on the right hand side is driven by the pinion 21 oppositely rotated from the pinion 21 driving the left hand reduction gearing, the motor housing will tend to rotate in the opposite direction to the operation of the drum 30. The result is that the pawl 40 will automatically be thrust in a right hand direction due to their cam surfaces out of engagement with the ratchet teeth 49 and into engagement with teeth 48 fixed to the drum 29, thus positively driving the latter and thereby winding in the cable 57 on the top side of the drum 29 while allowing paying out of the cable 58 on the lower side of the drum 30 and causing the latter to rotate in the same direction as the motor housing 11. Thus it will be seen that no matter which drum may be pulling a load, there will be substantially no relative movement between both of the drums and the motor housing. This operation is automatically taken care of.

While I have in this application specifically described two forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a hoist, a motor having a rotatably supported cylindrical casing, means driven from opposite ends of said motor for effecting rotation of said casing in opposite directions, a pair of relatively rotatable winding drums surrounding and journaled on said casing, and means for alternatively connecting said drums to said casing automatically in accordance with the direction of rotation thereof.

2. In a hoist, a motor having a rotatable cylindrical casing, means including manually operable slip control means operatively connected to the opposite ends of said motor for effecting rotation of said casing in opposite directions, a pair of relatively rotatable winding drums surrounding and journaled on said casing, and means for alternatively connecting said drums to said casing auto-

matically in accordance with the direction of rotation thereof.

3. In a hoist, a pair of relatively rotatable winding drums, a driving motor housed within said drums and comprising a rotor element rotatable about its own axis in only one direction, and a rotatable housing therefor, means driven by said motor for effecting rotation of said housing in opposite directions, and driving connections between said drums and housing for connecting one of said drums and said housing to rotate together during one direction of rotation thereof and to connect the other drums to said housing during the other direction of rotation thereof.

4. In a hoist, a pair of relatively rotatable winding drums, a driving motor disposed in said drums and comprising a rotor element rotatable about its own axis in only one direction, and a rotatable housing therefor, means driven by said motor for effecting rotation of said housing in opposite directions, and driving connections between said drums and housing including means governed by the direction of rotation of said housing for automatically connecting one or the other of said drums to said housing for positive rotation therewith and for releasing the other drum therefrom.

5. In a hoist, a pair of relatively rotatable coaxial winding drums, a driving motor having a unidirectionally rotative rotor element and a rotatable housing upon which said drums are journaled, means driven by said motor for effecting rotation of said housing in opposite directions, and means for connecting said drums to said housing for rotation therewith.

6. In a hoist, a pair of relatively rotatable winding drums, a motor disposed within said drums and having a rotatable casing, means driven by said motor for effecting rotation of said casing in opposite directions including selectively operable drive control mechanisms, and means for connecting one or the other of said drums to said casing automatically in accordance with the direction of rotation thereof.

7. In a hoist, a pair of relatively rotatable winding drums, a motor having a rotatable casing, means driven from opposite ends of said motor for effecting rotation of said casing in opposite directions, selectively operable slip control devices for controlling the drive of said casing, the casing rotating in one direction upon application of one of said devices and rotating in the opposite direction upon application of the other device, and means for connecting one drum or the other to said casing for rotation therewith.

8. In a hoist, a pair of relatively rotatable winding drums, a motor having a rotatable casing, means driven from opposite ends of said motor for effecting rotation of said casing in opposite directions, selectively oper-

able slip control devices for controlling the drive of said casing, the casing rotating in one direction upon application of one or said devices and rotating in the opposite direction upon application of the other device, and means for connecting one or the other of said drums to said casing automatically in accordance with the direction of rotation thereof.

9. In a hoist, a plurality of coaxial relatively rotatable winding drums, and means for supporting and for effecting selective rotation of said winding drums including a motor, a substantially cylindrical rotatable casing enclosing said motor and having said drums journaled upon its periphery, means driven by said motor for effecting rotation of said casing in opposite directions including during drive in each direction a gear carried by the casing and rotatable upon an axis parallel to but offset radially from the axis of the casing, a member carrying a gear with which said first mentioned gear is arranged to mesh during drum rotation, and releasable locking means for said gear carrying member, and means for locking one or the other of said drums to said casing for rotation therewith.

10. In a hoist, a plurality of coaxial relatively rotatable winding drums, and means for supporting and for effecting selective rotation of said winding drums including a motor, a substantially cylindrical rotatable casing enclosing said motor and having said drums journaled upon its periphery, means driven by said motor for effecting rotation of said casing in opposite directions including during drive in each direction a gear carried by the casing and rotatable upon an axis parallel to but offset radially from the axis of the casing, a member carrying a gear with which said first mentioned gear is arranged to mesh during drum rotation, and releasable locking means for said gear carrying member, means for locking one or the other of said drums to said casing for rotation therewith, automatically connecting one of said drums to said casing during rotation of the latter in one direction and the other drum to the casing during rotation of the latter in the other direction, and means under operator control for braking said drums at will.

In testimony whereof I affix my signature.
CHARLES F. OSGOOD.
